HENRIK A. HANSSON, OF GREENFIELD, CALIFORNIA.

CLEAT.

1,276,354.

Specification of Letters Patent.

Patented Aug. 20, 1918.

Application filed February 7, 1918. Serial No. 215,839.

To all whom it may concern:

Be it known that I, HENRIK A. HANSSON, a citizen of the United States, residing at Greenfield, in the county of Monterey and 5 State of California, have invented certain new and useful Improvements in Cleats, of which the following is a specification.

This invention is a cleat and has special reference to cleats which are used in connection with concrete molds.

One object of this invention is the production of a cleat which is so constructed as to be positioned upon a pair of boards and then be secured in a set position for 15 firmly retaining the boards in proper position upon a studding.

Another object of this invention is the production of a cleat which is in the form of a plate stamped from blanks provided 20 with a central opening, the plate being adapted to be positioned upon the inner surface of a pair of boards to hold the same in alinement with respect to their edges, although retaining means may be passed 25 through the central portion of the plate and then be secured to a studding in the rear of the boards where access may be had to the securing member.

In general the device consists of a plate 30 having a central opening and also a lug at one end, a headed securing means passing through the opening and terminating in a gripping element at its outer end, thus allowing a retaining element to be passed 35 through the gripping element, thus permitting the plate to be positioned upon the inner surfaces of a pair of boards to hold the edges of the boards in alinement, although the outer end of the securing element may 40 be retained or secured in engagement with a studding where access may be easily had thereto.

With the above and other objects in view, this invention consists of certain novel combination, constructions and arrangements of parts as will be hereinafter described and claimed.

One practical form of the construction of the present invention is hereinafter described, and is illustrated in the accompanying drawing, in which—

Figure 1 is a front elevation of the cleat in use, and

Fig. 2 is a section taken on the line 2—2 55 of Fig. 1.

In the use of the present invention, it

might be first well to state the manner in which the same is to be used. First of all, in the construction of molds or forms for concrete, the first wall is set up by the nailing or the securing otherwise of the boards of the wall to the usual studding or beams. In ordinary practice, the second wall is positioned adjacent the first wall and the thickness between these walls is the thickness of the finished concrete wall constructed by the mold. Owing to the limited space between the two walls, it is very difficult to secure the boards of the second wall to their studding, and it is difficult to swing the hammer or other driving element in the limited space.

In using the present invention, the first wall is set up in accordance with the practice above specified. The studding of the second wall is then placed in proper position and the boards 1 are positioned against the studding as indicated at 1'. In order to secure the boards 1 in position with the least amount of labor and to enable the ready removal of the board when desired, the present invention is employed.

The cleat comprises a plate 2 which is formed from a blank and which has its edges cut away, as shown at 3 to form a substantially diamond-shaped structure, which necessarily is broadest at its upper portion, although it tapers toward its ends. The plate 2 is provided with a central opening 4 for purposes to be hereinafter specified, while one end of the plate 2 is provided with a spur 5 extending at right angles thereto. This spur 5 is to be driven into the lower board 1 upon which the cleat is positioned, so as to hold the cleat against shifting. This spur is driven into the lower board as indicated at 6 and accomplishes the function above specified. The upper end of the plate is cut off as indicated at 7, thus eliminating a pointed upper end. The headed securing member 8 comprises a body having a cross head 9 thereon, while the opposite end of the body 8 is bent to form a hook 10 as illustrated clearly in Fig. 2. This body passes through the opening 4 formed in the plate 2 between the boards 1, thus bringing the head 9 into engagement with the surface of the plate 2. The hook 10 will then be bearing upon one side of the studding 1' and as this studding 1 110 will be upon the exterior of the second wall, it is obvious free access may be had

thereto, thus permitting a retaining nail or like element 11 to be driven into the studding 1' and to be engaged by the hook 10. It is obvious that this hook will therefore hold the securing element in firm engagement with the plate 2 and in this way the plate will be held against displacement. Owing to the plate being of a diamond-shaped structure, it is obvious that the plate intermediate its ends will be greatest, thus providing a structure which will compensate for the drawing action intermediate its ends caused by its securing at this point.

15 It is obvious that in assembling the second wall of the mold, the lower board is placed in position and then the cleat is positioned thereon and has its spur 5 driven thereinto, thus causing the cleat to extend beyond the upper edge of the board. The second board may be placed in position to be between the cleat 2 and the studding 1', and then the headed fastener may be passed through the opening to have its hook engaged by the nail or retaining element 11; thus holding the plate in a set position to positively hold the upper edges of the board in direct alignment with each other. Since the securing of the device takes place at a point exterior to the walls, as formed by the board 1, it is obvious the element passed through the hook 10 could be driven into the studding 1' since sufficient space is provided for the swinging of the driving element.

30 Where it is necessary to prevent marring of the inner surfaces of the boards 1, it is obvious that if so desired, the spur 5 may be flattened out or may not be provided, thus causing the plate to merely lay or fit firmly upon this board. It is further obvious that if so desired, an eye may be formed instead of the hook and the outer end of the retaining member and that instead of having the member of the specific form herein illustrated, an ordinary nail may be extended in the same manner and having the end bent to form a hook or eye. This of course, is very obvious as the fact that the specific shape of the plate may be changed without departing from the spirit of the invention, since, as above specified, only one form of the present invention is illustrated in the present case and obvious changes may be made in the construction of the device, as long as the changes do not exceed the scope of the invention as claimed.

What is claimed is:

1. In a concrete mold, the combination of a studding having boards positioned thereon, a plate bearing upon the inner surfaces of said boards, said plate having an opening formed therethrough, a headed fastener having a body extending through said opening and allowing the head to bear upon said plate, said body being bent to form a hook,

a retaining element carried by said studding and receivable within said hook, thus holding said plate to cause the plate to hold the edges of said boards in alignment.

2. In a concrete mold, the combination of studding, boards positioned upon said studding, fastening means engaging the surfaces of said boards for holding said boards in a set position upon said studding, said fastening means including a body bent to form a hook, a retaining element carried by said studding and receivable within said hook, thus holding said fastening means in a releasable set position.

3. In a concrete mold, the combination of studding, boards positioned on said studding, a plate bearing upon the inner surfaces of said boards, said plate having a spur thereon, said spur being adapted to be driven into one of the boards for holding the plate against accidental shifting, a headed fastener having a body extending through said plate, for holding the plate in a binding engagement with the boards, said body being bent to form a hook, a retaining element carried by said studding and receivable within said hook, thus releasably holding said boards upon said studding.

4. In a concrete mold, the combination of a studding, boards positioned on said studding, a plate bearing upon the inner surfaces of said boards to overlap a plurality of the boards, said plate being broad at its center and tapering toward its ends, thus being increased in width to increase its strength at the point where the greatest strain occurs thereon, and means for holding said plate in a binding engagement with the inner surfaces of said boards.

5. In a concrete mold, the combination of a studding, boards positioned on said studding, a plate bearing upon the inner surfaces of said boards, said plate being comparatively broad at its center and tapering toward its ends, a spur formed on one end of said plate for digging into a board, thus holding the plate against any tendency of accidental rotation, and means passing through the broad central portion of the plate for binding the same in a set position upon said boards.

6. In a concrete mold, the combination of a studding, boards positioned on said studding, a plate bearing upon the inner surfaces of said boards, said plate being comparatively broad at its center and tapering toward its ends, a spur formed on said plate for digging into one of said boards, thus holding the plate against any tendency of accidental shifting, a headed fastener passing through the central portion of said plate, and means for engaging the opposite end of said fastener for releasably holding the same upon said studding.

7. In a concrete mold, the combination of

a studding, boards positioned upon said studding, fastening means engaging the inner surfaces of said boards for holding said boards in a set position upon said studding, said fastening means including a body bearing upon said studding, and means releasably holding said body upon said studding.

In testimony whereof I affix my signature in presence of two witnesses.

HENRIK A. HANSSON.
